UNITED STATES PATENT OFFICE

2,482,263

ROLLER BIT

John S. Goodwin, Whittier, Calif., assignor to
 Globe Oil Tools Company, Los Nietos, Calif., a
 corporation of California

Application November 20, 1945, Serial No. 629,881

6 Claims. (Cl. 255—71)

1

This invention has to do with a roller type well drilling bit, commonly referred to as a rock bit, being that type of bit wherein cutting action is performed by rolling toothed cutters. It is a general object of the present invention to provide a bit of the general type referred to which is highly efficient and practical for digging tough rubbery shale formations such as are commonly referred to as brown shales.

It is a general object of my present invention to provide a bit of the general type mentioned with a pair of cutters having teeth arranged, proportioned and related so that a substantial proportion of the weight or force applied during drilling causes effective penetration of the teeth into the formation while a small proportion of the weight is carried or borne by cuttings lodged between the teeth. In the ordinary cutter for bits of the character referred to the teeth are such that a substantial proportion of the drilling weight is borne by cuttings wedged or lodged between the teeth or rows of teeth, and consequently there is but a limited pressure on the teeth causing them to penetrate the formation.

It is another general object of my present invention to provide a pair of cutters for a bit of the character mentioned in which the active parts, that is, the teeth which are arranged in rows, are so arranged, proportioned, and related that the cuttings are effectively cleared from between the teeth, with the result that the cutters are maintained in condition for active operation. By my invention I employ tapered cutters and the taper and mounting of the cutters is such that as the cutters work they do not have a true rolling action but rather have substantial slippage both at their inner and outer ends, thus wiping the formation cuttings from the grooves between the teeth, with the result that cuttings are worked lengthwise of the cutters between the teeth dislodging them so that the teeth are kept cleared and do not wedge tight as is the case if provision is not made for proper cleaning.

A further object of my present invention is to provide a pair of cutters for a bit of the character mentioned in which the teeth of each cutter extend, generally, lengthwise thereof, some of them being pitched in a slightly lefthand direction while others are pitched in a slightly righthand direction, the pitching of the teeth of the two cutters of the pair being generally opposite.

Another object of the invention is to provide an improved, highly efficient and effective tooth formation and relationship for cutters of the general type referred to. By my present invention I provide teeth of limited length axially but which are of substantial height, and which are spaced a substantial distance apart so that they

2

present limited points or cutting edges to penetrate the formation and afford ample clearance for cuttings.

The various objects and features of my invention will be fully understood from the following detailed description of a typical preferred form and application of the invention, throughout which description reference is made to the accompanying drawings, in which:

10 Fig. 1 is a side view of a well drilling bit embodying a pair of rollers incorporating my present invention, parts of the bit being broken away to show in section and to better illustrate the general construction. Fig. 2 is a side elevation taken as indicated by line 2—2 on Fig. 1. Figs. 15 3, 4 and 5 are views illustrating one cutter of the pair of cutters, Fig. 3 being a side elevation of the cutter, Fig. 4 being an end view taken as indicated by line 4—4 on Fig. 3, and Fig. 5 being a view taken as indicated by line 5—5 on Fig. 3. Figs. 6, 7 and 8 are views illustrating the other cutter, Fig. 6 being a side elevation, Fig. 7 being an end view taken as indicated by line 7—7 on Fig. 6, and Fig. 8 being a view taken as indicated by line 8—8 on Fig. 6.

25 My present invention is primarily concerned with a pair of roller cutters to be employed in a well drilling bit and the cutters that I provide can be used to advantage to cut the bottom or main portion of a well bore. In an ordinary or conventional type of rock bit where there are two crossed pairs of cutters I preferably employ my invention in connection with what are commonly termed the inner cutters, since this pair of cutters extends across a substantial portion of the bottom of the well bore. In the drawings 30 I have shown a typical application of my present invention and have there shown the invention applied to a pair of inner cutters of a typical rock bit which has both inner and outer cutters.

35 The rock bit shown in the drawings involves, generally, a body 10 having a tapered threaded mounting pin 11 projecting from its upper end and 40 having diametrically opposite depending side legs 12 between which the pair of inner cutters is carried. In the particular case illustrated the cutters are arranged on a common transverse axis and their inner ends are separated somewhat to 45 accommodate a central supporting web 13 which depends from the center of the body. The bit 45 illustrated involves outer cutters 14 carried by depending legs 15. However, my present invention is in no way concerned with the details of 50 these particular parts.

55 The pair of roller cutters that I provide is formed by a roller cutter X and a roller cutter Y, which are slightly tapered and which are rotatably supported between the legs 12 and also by 60 means of the center web 13. My present invention

tion is concerned primarily with the cutting parts or teeth of the cutters **X** and **Y** and not with the bearing means or other supporting means employed to rotatably support the cutters in the desired manner. For this reason I have merely indicated in a general way means supporting the cutters for rotation.

The two cutters **X** and **Y** are preferably substantially equal in length, in fact, they may be exactly equal in length and they are arranged so that their small ends are opposed or are adjacent the center supporting web 13 while their large ends are adjacent the inner sides of the supporting legs 12.

The cutter **X** has an inner row **A** of teeth, an outer row **B** of teeth, and intermediate rows **C** of teeth. The cutter **Y** is similarly formed with an inner row **A'** of teeth, an outer row **B'** of teeth, and intermediate rows **C'** of teeth. The rows of teeth of the two cutters that I have just referred to differ in two important particulars. First, the axial extent of the teeth of the two inner rows differs substantially and the axial extent of the teeth of the outer rows differs substantially, and the pitch of the teeth of the inner rows differs or is opposite while the pitch of the teeth of the outer rows differs, or is opposite. In the particular form of the invention illustrated the teeth of the row **A** of cutter **X** are of limited extent axially so that the row **A** may be said to be narrow while the teeth of row **A'** of cutter **Y** are of substantial extent axially so that the row **A'** may be said to be wide. Through this relationship or variation between the inner rows **A** and **A'** of the two cutters I gain an overlapping of the paths of these two rows of teeth and the path of the row **A'** is considerably wider than that of the row **A** and consequently projects considerably beyond that of the row **A**. In the case of the outer rows of teeth the row **B** of cutter **X** is of considerable extent axially and, therefore, the row **B** is wide while the teeth of row **B'** are of limited extent axially so that the row **B'** is narrow. The outer rows **B** and **B'**, being thus formed, have paths which overlap while the path of row **B** of cutter **X** projects or extends considerably inward beyond that of the row **B'** of cutter **Y**.

Adjacent rows of teeth of cutter **X** are spaced apart by deep grooves or channels 20 and in like manner adjacent rows of teeth of cutter **Y** are spaced apart by deep grooves or channels 20'. In accordance with my invention the grooves 20 between adjacent rows of teeth of cutter **X** are slightly wider than the crests 21' of the teeth of intermediate rows **C'** of cutter **Y**, while the grooves 20' of cutter **Y** are slightly wider than the crests 21 of the teeth of the intermediate rows **C** of cutter **X**. Furthermore, the intermediate rows of teeth of the cutters **X** and **Y** are located so that each intermediate row of teeth of one cutter tracks opposite a groove of the other cutter.

In accordance with my present invention the teeth of the several rows of each cutter extend generally lengthwise of the cutter but are pitched or inclined to extend somewhat around the axis of the cutter and so they do not extend truly lengthwise of the cutter. The term "pitch" is used to define the angular relationship of the teeth to the axis of the cutter other than that which may be incidental to the cutter being tapered as shown in the drawings. Some of the rows of teeth of each cutter are pitched in one direction while other rows are pitched in the opposite direction. In the particular case illustrated in the drawings the teeth of the outer row

B of cutter **X** are pitched lefthanded while the teeth of the remaining rows of that cutter are pitched righthanded. In the case of the cutter **Y** the teeth of the inner row **A'** and the adjacent intermediate row **C'** are pitched lefthanded while the teeth of the outer row **B'** and the adjacent row **C'** are pitched righthanded. Through thus varying the pitching of the teeth of each cutter and relating the pitching of the teeth of the two cutters, the teeth of the outer rows of the two cutters engage the formation at different angles and the teeth of the inner rows of the two cutters engage the formation at different angles, while the teeth of the intermediate rows of the two cutters do not track but engage the formation in staggered relation and also at varying angles all with the result that I eliminate entirely any tendency for the cutters to form a pattern into which the cutters fit and consequently track in a manner to check proper penetration of the formation.

In accordance with the preferred relationship or formation of teeth I make the length of the crest of each tooth approximately equal to the radial extent of the tooth. This, however, does not apply to the teeth of the outer row **B** of cutter **X** or the inner row **A'** of cutter **Y**, the crests of which are longer, nor to the teeth of the inner row **A** of cutter **X** and the outer row **B'** of cutter **Y**, the crests of which are shorter. In my preferred construction I space the teeth a substantial distance apart circumferentially, for instance, I prefer to space the teeth approximately one and one-half to two times the depth of the teeth. In order to accomplish this it is necessary to form fewer teeth at the small end of each cutter than at the large end. In the particular case illustrated I have provided 16 teeth at the large end of each cutter and only 12 at the small end.

In order to create the desired slippage and consequent cleaning action I do not form the cutters to be conical or in a manner to have true rolling action, but rather taper them only slightly as shown in the drawings, and arrange and proportion them so that the plane of true rolling contact between each cutter and the formation is approximately one-third of the length of the cutter from the outer end thereof. In such case points on each cutter outward of such plane roll faster, all with the result that there is not true rolling contact of the teeth with the formation but rather slippage and consequent effective digging action. The slipping further aids in keeping the cutters clean as there is a tendency for the cuttings to be wiped or pushed from the grooves between the rows of teeth and from between the teeth themselves as the tool operates. Furthermore, the wide circumferential spacing of the teeth compared with depth of tooth acts to materially aid in allowing the cuttings to clear themselves from the teeth. These several factors all contribute to freeing the teeth for greater penetration and consequent effective drilling action.

In addition to the cleaning action gained by the construction and relationship that I have above described I provide the bit body with general openings 30 which direct circulating fluid onto the upper parts of the rollers so that the rollers are effectively washed as they operate. By forming the teeth so that their crests are short relative to the grooves or spaces between them, and yet relating the rows of teeth and the grooves so the grooves are only slightly wider than the rows of teeth, the formation is effectively removed and yet the teeth have limited parts en-

tering the formation so that there is a high penetrating pressure to cut the formation.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. In a well drilling bit including, a body, and a pair of tapered roller cutters carried by the body with their small ends opposed, each cutter having a plurality of spaced rows of teeth, the teeth of each row being pitched relative to the longitudinal axis of the cutter on which they occur and the row of teeth at the inner end of one cutter being wider than the row of teeth at the inner end of the other cutter and the row of teeth at the outer end of the first mentioned cutter being narrower than the row of teeth at the outer end of said other cutter, the teeth of the inner row of the first-mentioned cutter being pitched in a common direction opposite to the teeth of the inner row of said other cutter, the teeth of the last mentioned row being pitched in a common direction, the teeth of the outer row of the first mentioned cutter being pitched in a common direction opposite to the teeth of the outer row of said other cutter, the teeth of the last mentioned row being pitched in a common direction.

2. In a well drilling bit including, a body, and a pair of tapered roller cutters carried by the body with their small ends opposed, each cutter having a plurality of spaced rows of teeth, the teeth of each row being pitched relative to the longitudinal axis of the cutter on which they occur and the row of teeth at the inner end of one cutter being wider than the row of teeth at the inner end of the other cutter and the row of teeth at the outer end of the first mentioned cutter being narrower than the row of teeth at the outer end of said other cutter, the teeth of the inner row of the first-mentioned cutter being uniformly pitched opposite to the teeth of the inner row of said other cutter in which the teeth are uniformly pitched, and the teeth of the outer row of the first mentioned cutter being uniformly pitched opposite to the teeth of the outer row of the said other cutter in which the teeth are uniformly pitched, the teeth at the inner ends of the cutters being pitched opposite the teeth at the outer ends of the cutters.

3. In a well drilling bit including, a body, and a pair of tapered roller cutters carried by the body with their small ends opposed, each cutter having a plurality of spaced rows of teeth, the teeth of each row being pitched relative to the longitudinal axis of the cutter on which they occur and the row of teeth at the inner end of one cutter being wider than the row of teeth at the inner end of the other cutter and the row of teeth at the outer end of the first-mentioned cutter being narrower than the row of teeth at the outer end of the said other cutter, the teeth of the inner row of the said first-mentioned cutter being pitched opposite to the teeth of the inner row of the said other cutter and the teeth of the outer row of the said first mentioned cutter being pitched opposite to the teeth of the outer row of the said other cutter.

4. In a well drilling bit including, a body, and a pair of tapered roller cutters carried by the

body with their small ends opposed, each cutter having a plurality of spaced straight rows of teeth, the teeth of each row being pitched relative to the longitudinal axis of the cutter on which they occur and the row of teeth at the inner end of one cutter being wider than the row of teeth at the inner end of the said other cutter and the row of teeth at the outer end of the first-mentioned cutter being narrower than the row of teeth at the outer end of the said other cutter, the teeth of the inner row of the said first-mentioned cutter being pitched opposite to the teeth of the inner row of the said other cutter and the teeth of the outer row of the said first mentioned cutter being pitched opposite to the teeth of the outer row of the said other cutter.

5. In a well drilling bit including, a body, and a pair of tapered roller cutters carried by the body with their small ends opposed, each cutter having a plurality of axially spaced straight rows of teeth, the teeth of each row being pitched relative to the longitudinal axis of the cutter on which they occur and the row of teeth at the inner end of one cutter being wider than the row of teeth at the inner end of the other cutter and the row of teeth at the outer end of the first mentioned cutter being narrower than the row of teeth at the outer end of the said other cutter, the teeth of the inner row of the first-mentioned cutter being uniformly pitched opposite to the teeth of the inner row of the said other cutter in which the teeth are uniformly pitched, and the teeth of the outer row of the first-mentioned cutter being uniformly pitched opposite to the teeth of the outer row of the said other cutter in which the teeth are uniformly pitched, the teeth at the inner ends of the cutter being pitched opposite to the teeth at the outer ends of the cutters.

6. A well drilling bit including a body and a pair of uniformly tapered coaxial roller cutters carried by the body with their small ends opposed, each cutter having a plurality of spaced rows of teeth, the teeth of each row being pitched relative to the longitudinal axis of the cutter on which they occur, and the teeth of one cutter being pitched opposite to those of the corresponding teeth of the other cutter, the row of teeth at the inner end of the one cutter being wider than the row at the inner end of the other cutter and the row of teeth at the outer end of the first mentioned cutter being wider than the row at the outer end of said other cutter, the taper of the cutters being related to their length and diameters so the plane of true rolling contact of each cutter with the formation being cut is removed from the outer end of the cutters a distance substantially equal to one third of the length of the cutter.
